ELEVATOR CONTROL SYSTEM

Leopold J. Guay, Flushing, N. Y.

Application August 31, 1948, Serial No. 47,091

22 Claims. (Cl. 187—29)

1

This invention relates to improvements in control systems for elevators, and has for an object the provision of an automatic system for maintaining predetermined spaced intervals between the levels of the cars other than at the bottom or top floors, particularly in buildings having a large number of elevators and heavy passenger traffic.

Another object of the invention is the provision of means for preventing congestion of elevator cars at any levels in the elevator shafts while they are traveling in either direction.

A further object of the invention is the provision, in an elevator system, of instrumentalities correlated with the movement of the cars in both directions at all times for controlling the elevators so as to increase the efficiency of the entire system by eliminating all lost motion and duplication of effort.

Another object of the invention is the provision of a plurality of sets of instrumentalities including "on" and "off" photo-electric cells and projection or exciting lamps, one set for each elevator; each set being moved along a predetermined path in definite time relation to the movement of its elevator, whereby the exciting lamp of one elevator passing over the "on" or "off" photo-electric cell of another elevator will cause an impulse to be delivered to the by-pass relay of the latter elevator.

With present elevator systems, it is common knowledge that many times two or more elevators going in the same direction stop at a given floor at about the same time. The direction lights of these elevators on that floor light up, respective to the time they stop, showing the direction to the prospective passengers. This confuses them as to which elevator to enter and often they will take an elevator that is discharging passengers and which should not pick up passengers, or they might enter different elevators and consequently slow down the service.

My new and improved system will eliminate this by automatically bypassing the bypass relays of all elevators, except the one which will stop at that floor for the purpose of picking up passengers, and if another elevator stops at the same floor to discharge passengers, the signal light of the first car will go out and the prospective passengers, if any, will be directed to move toward the second elevator to arrive at that floor, which in turn will give the first elevator a chance to clear the second elevator so that the latter may receive passengers.

It is also known that frequently, many eleva-

2

tors are congested at some levels in the elevator shafts and they are manually separated by the starter on the ground floor. This method is very inefficient because it is beyond human control to separate them evenly when such congestion occurs at two or more levels at one time. This results in loss of time for prospective passengers, irregular service, and it raises the cost of operation both for electricity and manpower.

10 In my new and improved system, the separation of the elevator cars is not based on the time of travel of the elevators, but instead is based on maintaining a substantially even spacing apart of the elevators in the shafts and maintaining them in substantially such spacings, except at the tops and the bottoms of the shafts.

Other objects of the invention will be apparent to those skilled in the art upon a study of the specification and the accompanying drawings.

15 20 Referring to the drawings, which are merely given by way of example to carry out the invention:

Figure 1 is an elevation of a plurality of mechanisms, each moving in definite timed relation to

25 the movement of a different car in the elevator shaft, one mechanism being moved in timed relation to one car, another in timed relation to another car, etc.

Figure 2 is a plan view of one of the mechanisms, as seen along the lines 2—2 of Figure 1;

30 Figure 3 is an enlarged plan view of a set of instrumentalities for advancing a moving arm in one direction when the car is traveling up the shaft and in the opposite direction when the car is moving down the shaft;

35 Figure 4 is an elevation of a portion of one of the moving arms showing mechanism for increasing its length when the car associated therewith is moving in one direction and for decreasing its length when the car is moving in the opposite direction;

40 Figure 5 is a sectional elevation, taken along the lines 5—5 of Figure 4, showing further details of the moving arm;

45 Figure 6 is a circuit diagram, showing the circuits employed in each of the mechanisms shown in Figure 1;

Figure 7 is a circuit diagram of the sources of electronic currents, which are interconnected with the circuits shown in Figure 6; and

50 Figure 8 is a diagrammatic representation of an elevator cam actuating one of the limit switches.

Referring first to Figure 1, my new and improved elevator control system includes a plural-

ity of moving an arm assemblies, designated generally by the numerals 20, 21, 22 and 23. One of these arm assemblies is provided for each elevator and is moved in time with the movement of the elevator car with which it is associated, in one direction when the car is descending, and in the opposite direction when the car is ascending. Although these arm assemblies and the mechanisms for moving them are identical, they have been given different numerals in order to clarify the description of the operation.

The arm assembly 20 includes a sleeve 24 which is journaled on a vertical shaft 25 and which rests on a thrust bearing 26 mounted on the fixed shaft 25. Secured to the sleeve 24 is an arm 27. The arm 27, to one side of the sleeve 24, carries a counterweight 28. On the other side of the sleeve 24, the arm has an elongated channel 29 formed therein and on the extreme left end of the arm, as seen in Figure 1, the channel 29 has restrictions 30 and 31 formed therein to accommodate an extension of a movable member positioned in the channel 29. For securing the rollers 35 and 36 in the channel, is an overhanging strip 38 and for securing the rollers 37 and 38 in the channel, an overhanging strip 40 is provided. These strips are secured to the channel by means of screws 41. Secured to or formed integral with the block 34 is an extension 42 which engages the rollers 32 and 33 and which extends toward the left, as seen in Figures 1, 2 and 4.

The extension 42, as may best be seen in Figure 2, carries an arcuate support 43. The extension 42 has an elongated central slot 44 formed therein, leaving the extension substantially lighter in weight and yet stronger.

Referring again to Figure 4, the block member 34 has spaced parallel bosses 45, 46 extending laterally therefrom. These bosses have aligned holes formed therein to accommodate a bolt 47.

Mounted on the arm 27, to the left of the sleeve 24 are solenoids J₁ and J₂. These solenoids are in alignment with each other and carry a common plunger 48. Secured to the plunger 48 at a point intermediate the ends thereof is a bracket 49 which has a depending extension 50. The roller end of the extension 50 has a hole formed therein through which the bolt 47 also passes.

In my system, for convenience, I energize the solenoid J₁ when the car associated with that arm is traveling upwardly and I energize the solenoid J₂ when the car is traveling downwardly. The arcuate support 43 carries exciting lamps and photo-electric cells which cooperate with other exciting lamps and/or photo-electric cells carried by others of said arms, and these are in one relative position on the arm when the car associated with that arm is traveling in one direction and they are in another relative position when the car associated with that arm is traveling in the opposite direction, as will presently be described herein.

The support 43 carries the following equipment: an exciting lamp E₁ which might be termed the "up" exciting lamp; a second exciting lamp E₂ which might be termed the "down" exciting lamp; a photo tube D₁ for controlling the "up" direction "on" relay; a photo tube D₂ for controlling the "down" direction "on" relay; a photo tube F₁ for controlling the "up" direction "off" relay; and a photo tube F₂ for controlling the "down" direction "off" relay.

The upper end of the shaft 25 (Figures 1 and 2) is supported in a boss 51 having formed integral therewith angular bracket arms 52 and 53, with

integral foot plates 54 and 55, respectively bolted to a frame member 56 by means of bolts 57. The boss 51 may carry set screws 58 which engage the shaft 25 and steady the structure.

Extending toward the left, as seen in Figure 1 and omitted from Figure 2 for the sake of clarity, is an arm 59, which may also be formed integral with the boss 51. Secured to the arm 59 by means of bolts 61 are spaced bracket members 60, between which are mounted solenoids C₁ and C₂ which are secured to the bracket members by means of screws 62. Also secured to the arm 59 by the screws 61 is an extension 63 having an integral foot plate 64 which is secured to the frame member 66 by means of bolts 65.

Secured to the sleeve 24 is a sector 66, having a hub portion 67 embracing the sleeve and secured thereto by means of screws 68. This sector, as may be seen in Figure 3, has a series of notches with slots therebetween numbered from 1 to 12 and representing that the building in which it is used has twelve floors. If the building had fewer floors, the number of notches would correspond to the number of floors which would be less. It will be noted that these notches are numbered "1" to "12" in a clockwise direction, and in my apparatus it would be moved, in a counter-clockwise direction, in time with the arrival of the elevator car with which it is associated at the corresponding floor as the car is moving in an "up" direction, for example, when the car reaches the fourth floor, the solenoid C₁ (through mechanism to be presently described) has moved or advanced the sector in steps, the last notch engaged by said mechanism being number 4. When the car is at the sixth floor, notch number 6 is engaged by the mechanism, etc.

The sleeve 24 also has secured thereto in spaced relation to the sector 66, a second sector 70, having a hub portion 69 embracing the sleeve and secured thereto by means of screws 71. The sectors 66 and 70, in addition to being spaced apart on the sleeve axially, are oppositely disposed angularly as may be seen in Figure 3. The notches in sector 70 face in the opposite direction, and they are numbered "1" to "12" in a clockwise direction, although this sector, when moved by its solenoid C₂ in a clockwise direction (as will presently be described) is moved in time with the movement of the car in the "down" direction. This means that when the car is at the twelfth floor, the number "12" notch is engaged; when the car is at the seventh floor, the number "7" notch is engaged, etc.

Since the mechanisms actuated by the solenoids C₁ and C₂ are identical, only one of them is described in detail and the corresponding elements in the two are given the same numerals.

Referring to Figure 3 the solenoid has a plunger 72 which reciprocates in the interior bore 73 thereof. The lower end of the solenoid has aligned lugs 74 formed thereon between which a pawl member 75 extends. These lugs and the pawl member have aligned holes therethrough and a clevis pin 76 forms a pivotal support for the pawl member, and normally the pawl member bears against the bottom face of the plunger 72, and is so held by a spring 77, the lower end of which engages a cotter pin 78 in the pawl member 75, and the upper end of which engages a cotter pin 79 in a guide bar 80, which is secured to the plunger 72 in spaced relation to the lower end thereof.

The guide bar 80 has a bearing hole therein which engages a vertical guide rod 81 which is

carried on the solenoid head 82 and projects downwardly parallel to the plunger 72. The guide rod 81 has an angular portion 83 which forms a stop defining the lowest position of the plunger. Between the guide bar 80 and the head 82 is a spring 84 which cushions the action of the plunger 72 and insures its return to its normal position after the solenoid winding is de-energized.

Spaced apart from and parallel to the plunger 72 is a bar 85, the lower end of which is bifurcated and pivotally connected to the pawl member 75 by means of a pivot pin 86 passing through aligned holes in the bifurcation and in the pawl 75. Spaced link members 87 are pivotally connected to the upper end of the bar 85 by means of a pivot pin 88, and the link members 87 are pivotally connected to the plunger 72 by means of a pivot pin 89 extending through suitable holes therein. Arcuate clearance spaces, one of which is shown at 90, in the plunger, provide clearance spaces for the movement of the link members.

The bar 85 is of such length that when its upper end encounters the head 82, the pawl 75 has moved or advanced the sector, which it actuates, one notch each time the solenoid is energized.

When the solenoid is de-energized, the plunger returns to its normal position defined by the stop 83 and while so doing, the pawl "ratchets" over the next notch below (which is the one which it will actuate next) and assumes the position shown in Figure 3 wherein its end clears all of the notches, and permits them to move past it in either direction.

Now, as to how the impulses are initiated for energizing the solenoid, refer to Figure 8. The elevator car, shown fragmentarily at 91, has secured thereto a cam member 92 supported by brackets 93 and 94. In the elevator shaft in the path of travel of the car is a plurality of switch members, such as the switch member 95, one such switch member being provided for each floor in each elevator column. These switch members exist in elevator columns now and are called limit switches.

Referring now to Figure 6, which shows the circuit diagrams of my system, it will be noted that the array of twelve limit switches is so connected that the switches are each connected in parallel from a conductor 96 to a conductor 97. The conductor 96 is connected to the negative side of a source of current, and the conductor 97 is connected to a branch conductor 98 connected to one terminal of the winding of each solenoid C₁ and C₂.

A conductor 99 leads from the positive side of said source to a bus bar 100 in the motor magnetic direction control 101 (which is standard equipment on existing elevators). This bus bar is connected to a contact in the "up" section of the control 101, and is also connected to a contact in the "down" section of said control. The contact in the "up" section, corresponding to the one referred to above, is connected via a wire 102 to the other end of the winding of the solenoid C₁ (up). The corresponding contact in the "down" section of the control 101 is connected via a wire 103 to the other terminal of the solenoid C₂.

Thus, it will be evident that as an elevator moves up or down in the shaft, the limit switches are sequentially actuated and a series of impulses is delivered to the winding of the solenoid C₁ when the elevator is ascending, or to the

solenoid C₂ when the elevator is descending. Each impulse received by either solenoid causes its plunger to move upwardly, as seen in Figure 3, and consequently the sector associated with that solenoid is advanced one notch. For example, for each impulse received by the solenoid C₁, as the elevator is ascending, the pawl member 75 advances the sector 66 in a counter-clockwise direction one notch, and consequently, the arm 27, for example, is rotated about the shaft 25 one step in a counter-clockwise direction for each impulse received by the solenoid C₁; thus, the arm 27 is moved in a counter-clockwise direction in definite relation with the movement of the elevator, as it ascends in the shaft. Even though the car moves continuously up the elevator shaft, the arm is moved in steps or increments in time with that movement. When the elevator is descending, the impulses are delivered to the solenoid C₂ and its pawl advances the sector 79 in a clockwise direction and moves the arm 27 in a clockwise direction, as viewed from above.

Referring to the circuit diagram, Figure 6, the motor magnetic direction control, which is standard equipment on the elevator, and which is indicated diagrammatically at 101, in Figure 6, is in the position shown in the drawing, with the switch arm 104 moved downwardly and with the switch arm 105 moved upwardly, when the car is descending, and when the car is ascending, the switch arm 105 is moved downwardly and the switch arm 104 is moved upwardly.

Now, in the first instance, that is to say, when the car is moving downwardly, the switch blade 106 connects its cooperative contacts together, so that the impulses instituted by the limit switches 95 in the elevator shaft, as the elevator moves along, are delivered to the solenoid C₂. This circuit may be traced on the diagram as follows: from the positive terminal of the source of current 107 via the conductor 99 to the cross-connector 100, thence via the blade 106 to the conductor 103 which leads directly to one terminal of the solenoid C₂, continuing from the other terminal of the solenoid C₂ via the cross-connection 98 and thence via the wire 97 to the limit switches 95 and thence via the conductor 66 to the negative side of the source 107.

When the car is traveling upwardly in the elevator shaft, the switch arm 105 of the control 101 is moved downwardly and the switch arm 104 is moved upwardly, and the circuit may be traced as follows: from the positive side of the source 107 via the conductor 99 to the cross-connection 100 and thence via the switch blade 108 to the conductor 102 which leads directly to one terminal of the solenoid C₁. From the other terminal, the circuit continues via the wire 98, the conductor 97, the limit switches and thence via the conductor 96 to the negative side of the source 107.

Continuing with the description of Figure 6, the solenoids J₁ and J₂ have corresponding terminals interconnected by a conductor 109 to which one end of a conductor 110 is connected. The other end of this conductor is connected to the negative side of a source of current 111. The other terminal of the solenoid J₁ is connected via a conductor 112 to a contact in the "up" section of the magnetic direction control 101, which cooperates with switch blade 113. The other contact cooperating with the switch blade 113 is connected via cross wire 114 to a contact in the "down" section of the control 101 which is contacted by a switch blade 115. The other contact

in the "down" section of the control 101, which cooperates with the switch blade 115, is connected via a wire 116 to the other terminal of the solenoid J₂.

The cross wire 114 is connected via a wire 117 to the positive side of the source 111, so that when the control 101 is in the position with its switch arm 104 moved downwardly, the circuit to the solenoid J₂, which is the "down" solenoid, may be traced as follows: from the negative side of the source 111 and via the conductor 110 to the cross-connection 109; thence, to one terminal of the solenoid J₂; then, from the other terminal of J₂ and via the conductor 116 to the contact and via the switch blade 115 to the cross connection 114 and thence via the conductor 117 to the positive side of the source 111.

Now, with the switch arm 105 moved downwardly in the up section of the control 101, the circuit for the solenoid J₁ may be traced as follows: from the negative side of the source 111 via the conductor 110 to the cross conductor 109 and thence to one terminal of J₁; then, from the other terminal of J₁, via the conductor 112 to a contact, which is then contacted by a switch blade 113 and thence to the cross conductor 114 and via the conductor 117 to the positive side of the source 111. Thus, it will be seen that whenever the motor magnetic direction control 101 of the elevator is shifted so that the switch arm 104 in the "down" section thereof closes its contacts, current will be supplied to the solenoid J₂; on the other hand, when the switch arm 105 in said control is moved downwardly so that its switch blades engage the contacts, energy is supplied from the source 111 to the solenoid J₁ and this always occurs when the elevator is ascending.

The motor magnetic direction control 101 controls the connections to the photo tubes and the exciting lamps; for example, the exciting lamps E₁ have common terminals thereof connected via a wire 118 to a wire 119, and thence to one side of a source of current 120. From the other side of the source 120, a wire 121 is connected to a cross-wire 122, one end of which is connected to a contact which cooperates with a switch blade 123 on the switch arm 104 of the control 101 and the other end of which is connected to a contact which cooperates with the switch blade 124 on the switch arm 105 of the control 101. A wire 125 has one end connected to the other contact cooperating with the switch blade 124, and has its other end connected to the other common terminals of the exciting lamps E₁, so that when the switch arm 105 in the up section of the control 101 is down, current is supplied to the exciting lamps E₁.

The wire 119 is also connected to one set of common terminals of the exciting lamps E₂ and the other common terminals of these exciting lamps are connected together and connected via a wire 126 to the other contact with which the switch blade 124 cooperates, so that when the switch arm 104 of the control 101 is down, the exciting lamps E₂ are supplied with current from the source 120.

The photo tubes F₁ are connected via a wire 127 to a switch contact in the up section of the control 101 with which the blade 128 on the switch arm 105 cooperates. The other contact with which the switch blade 128 cooperates is connected by cross-wire 129 to a contact with which the blade 130 in the down section of the control 101 cooperates. A wire 131 has one end connected to the cross-wire 129 and the other

end terminates in the diagram, Figure 6, at B₂ which means that it is connected to a wire 132, in Figure 7, which is also marked B₂. This wire connects through a condenser 133 to the midpoint of a potentiometer 134, one end of which is connected to the cathode 135 of the amplifier tube 136, and the other end of which is connected to the high voltage winding 137 of a transformer 138. The plate 139 of the tube 136 has a wire connection 140, which is labeled "B₃" and which is intended to be connected to the end of a wire 141, which is also labeled "B₃," in Figure 6. The wire 141 connects to one terminal of a solenoid 142 which urges the selective bypass relay 143 to the left, or "off" direction, as seen in Figure 6. The other end of the solenoid 142 is connected via a wire 144, which is labeled "B₁," to a wire 145, in Figure 7 (which is also labeled "B₁"), and thence via a meter 146 and a wire 147 to the other end of the high voltage winding 137 of the transformer 138. The other common terminals of photo tubes F₁ are connected via a wire 148 to a branch wire 149, to which the wire 144 is connected.

25. The "down" direction "off" photo tubes F₂ have their common terminals on one side connected via a wire 150 to the junction of the wires 148 and 149, so that the return circuit of the photo tubes F₂ is common with the return circuit of the photo tubes F₁. The common terminals on the other side of the photo tubes F₂ are connected via a wire 151 to a contact which is contacted by the switch blade 130 on the arm 104 when the control 101 is thrown in the down direction. This completes the circuit which, in effect, connects 30 151 and 129 together, so that the circuit continues from 129 via the wire 131 to B₂, on Figure 6, and thence to B₂, on Figure 7, and via the wire 132 to the grid of the tube 136 and via the condenser 133 to the midpoint of the potentiometer, just as described above in connection with the photo tubes F₁, so that when the motor magnetic direction control 101 is in the down position, the photo tubes F₂ are connected to the amplifier tube 136, and when the control 101 is thrown to the up position, the photo tubes F₁ are connected to the amplifier tube 136.

35. The "up" direction "on" photo tubes D₁ and the "down" direction "on" photo tubes D₂ all have one side thereof connected in common and interconnected via wires 152 and 153, respectively, to a wire 154, which connects to one terminal of the "on" solenoid 155 of the selective bypass relay. The branch wire 156 connects to the wire 40 154 and is labeled "A₁," in Figure 6.

45. Referring now to Figure 7, a wire 157, connected to a meter 158, has its free end also labeled "A₁," and is connected to the end A₁ of the wire 156. A wire 159 is connected to the return end of the high voltage winding 160 of a transformer 161.

50. The other common terminals of the "up" direction "on" photo tubes D₁ are connected in common and are connected via a wire 162 to a contact which is engaged by the switch blade 163 on the arm 105 of the motor magnetic direction control 101. The other contact with which the blade 163 cooperates, is connected via a cross-wire 164 to a contact which cooperates with the switch blade 165 on the arm 104 of the control 101. A wire 166 has one end connected to the cross-wire 164 and its other end is labeled "A₂" in Figure 6, and is connected to a wire 167, shown in Figure 7, and also labeled "A₂." This wire connects to the grid of an amplifier tube 168 and is also connected

via condenser 169 to the midpoint of a potentiometer 170.

One end of the potentiometer is connected to the cathode 171 of the tube 168 and the other end of the potentiometer is connected to the transformer winding 160. The cathode of the tube 136 is also connected to a tap on the winding 137 and the cathode 171 of the tube 168 is connected to a tap on the winding 160. The primaries of the transformers 138 and 161 are connected in parallel and are connected via a switch 172 to a source of current 173. The plate of the tube 168 has one end of a wire 174 connected thereto. The other end of this wire is designated as "A₃."

Referring back to Figure 6, a wire 175, also labeled "A₃," is connected to the other side of the solenoid winding 155 of the selective bypass relay, so that when the motor magnetic direction control 101 is shifted to the down position, any light shining on the "down" direction "on" photo tubes D₃, causes the solenoid 155 to be energized, and therefore effects the shifting of the selective bypass relay 143 to the "on" position. Now, when the direction control 101 is thrown to the "up" position, any light shining on the "up" direction "on" photo tubes will effect the energization of the solenoid 155 and shift the selective bypass relay 143 to the "on" position.

Contrasted with this, when the control 101 is in the "down" position, any light shining on the "down" direction "off" photo tubes F₂ will effect the energization of the solenoid 142 and shift the selective bypass relay 143 to the "off" position. Likewise, when the control 101 is in the "up" position, any light falling on the "up" direction "off" photo tubes F₁ will effect the energization of the solenoid 142 and shift the selective bypass relay 143 to the "off" position.

Referring to Figure 2, the following description of the "up" and "down" positions of the sectors 43 and the exciting lamps and photo tubes carried thereby, is now given to show the effects produced by the circuits described in Figures 6 and 7, when the motor magnetic direction control 101 is in the "down" position and when it is in the "up" position. When the control 101, in Figure 6, is in the "down" position (the position shown in solid lines in Figure 6) the solenoid J₂ is energized, with the result that the arm 42 carrying the sector 43 is moved to the right, and all cars which are descending will have their corresponding sectors 43 moving on concentric paths about the axis 25 on a short radius. At the same time, circuits are completed to supply energy to the exciting lamp E₂ and the circuits between the photo cell F₂ and the solenoid 142 of the bypass relay 143 are completed; also, at the same time, circuits between the photo cell D₂ and the solenoid 155 of the selective bypass relay are completed, and all of the circuits to E₁, F₁, and D₁ are disabled.

Now, since the sectors of all of the elevators which are descending move about the same radius, interaction between the exciting lamp E₂ on one of the elevators and the photo cells F₂ and/or D₂ is effected if one or more of the elevators is going too slow and gets behind or if one or more of the elevators is going to fast and overtakes one or more of the others, and the selective bypass relay of the shaft in which it or they are moving is thrown to an "off" position if the photo tube F₂ receives light or it is thrown to the "on" position, if and when the photo tube D₂ receives light.

When the motor magnetic direction control 101

is thrown to the "up" position, that is to say, with the switch blades carried by the arm 104 raised out of contact with their cooperating contacts and with the switch arm 105 moved downwardly, so that its blades cooperate with their cooperating contacts, the solenoid J₁ is energized, with the result that the arm 42a carrying the sector 43a is moved outwardly, so that its radius about the center of the shaft 25 is substantially increased. As this occurs, the exciting lamp E₁ is supplied energy from a source of current and circuits are completed between the photo tube F₁ and the solenoid 142 on the selective bypass relay 143 and circuits are also completed between the photo tube D₁ and the solenoid 155 of the selective bypass relay 143. The circuits to the exciting lamp E₂ and the circuits of the photo tubes F₂ and D₂ are disabled.

The selective bypass relay, as will be noted in Figure 6, has a pair of contacts for the "off" position. One of these contacts is connected via a wire 175, which is connected to one side of the source 120. The common wire 119 for the exciting lamps E₁ and E₂ is connected in series with a pair of contacts 176, which are normally closed so that in effect the wire 119 is connected to the plus side of the source 120.

The other contact of the relay 143 is connected via a wire 177 to one terminal of the winding 179 of a relay 178. The other terminal of the winding 179 is connected by a wire 180 to the wire 120 which leads to the negative side of the source 120.

A switch 181 is connected from the positive side of the source 120 to the wire 175 and a second switch 182 is connected in the same manner. The switch 181 might represent the operator's bypass switch in the elevator car and the switch 182 might represent a bypass switch for the starter to use on the ground floor.

Whenever the contacts of the relay 143 or either of the switches 181 or 182 are closed, a winding 179 of the relay 178 is energized, thereby attracting the armature 183 and opening the contact points 176, disabling the return circuit 119 of the exciting lamps E₁ and E₂.

The switches 181 and 182 are consequently manual controls for bypassing and the relay 143 is an automatic control for bypassing which is effective when the "off" photo cells F₁ or F₂ for one car receive light from the exciting lamp moving in unison with the movement of another car going in another direction. This causes the solenoid 142 to be energized, thereby moving the armature to the "off" position with the result that in addition to being bypassed, the exciting lamp moving in unison with the bypassed car is extinguished.

Now, after the mechanism moved by the car which has been bypassed has cleared the mechanism of the car that bypassed it, or has cleared the mechanism moving in unison with any other car in that path, its photo tube D receives light from one of the other exciting lamps and the solenoid 155 is energized, thereby shifting the selective bypass relay to the "on" position, which opens the "off" position contacts. This de-energizes the winding 179 of the relay 178 and allows the contacts 176 to close again; thus, the car that was bypassed is back in service and its exciting lamp is again burning.

Bridging the wires 96 and 97, in addition to the limiting switches 1-12, is a pushbutton switch 185, by means of which the starter may step the apparatus forward to bring it in synchronism

with its car, in case it gets out of synchronism. This pushbutton is effective in either direction, the direction depending upon the position of the motor magnetic direction control 101, and usually, such adjustments or checks are effected either when the car is at the top floor or the bottom floor, and an example of its use is as follows: Suppose the moving arm of a given car is one step out of synchronism with the car and is either at the top floor or the main floor. The starter may push the button 185 any number of times; for example, suppose he pushes it a half dozen times; the arm, which was supposed to be one step out of synchronism, would advance that one step upon the first push and the other impulses supplied to the solenoid C₁ or C₂ would have no effect because the arm, after moving the one step, is at the end of its movement in that direction, and since the car is also at the end of its travel in that direction, synchronism is ensured.

Now, since the sectors of all of the elevators which are ascending move about the longer radius, interaction between the exciting lamp E₁ on one of the elevators and the photo cells F₁ and/or D₁ is effected, if one or more of the elevators is going too slow and gets behind or if one or more of the elevators is going too fast and overtakes one or more of the others, and the selective bypass relay of the shaft in which it or they are moving is thrown to an "off" position if the photo tube F₁ receives light or it is thrown to the "on" position, if and when the photo tube D₁ receives light.

In Figure 1, the moving arm assembly 20 and the moving arm assembly 21 are shown with their exciting lamps and photo cells shifted to the "up" position and the assemblies 22 and 23 have their photo cells and exciting lamps shifted to the "down" position, so that the relation between the assemblies moving in unison with two "up" cars may be seen and so that the relation of the assemblies controlled by two "down" cars may be seen.

From the above, it will be seen that the purpose of the "on" photo tubes D₁ and D₂, regardless of whether the elevator is ascending or descending, is to keep the car No. 1 in service until the exciting lamp E of elevator No. 2, for example, passes over the "off" photo tube F of the No. 1 car. As soon as this occurs, car No. 1 is bypassed and its exciting lamp E. No. 1 car) is cut off at the same time so that it will have no effect on the photo tubes F and D of any of the other cars, and therefore, it will not go back into service again until the "on" photo tube D receives light from the exciting lamp of the No. 2 car of any of the other cars, going in the same direction, the exciting lamps of which may shine upon the "on" photo tube D.

The action of photo tube D, therefore, prevents an elevator that has been bypassed from remaining out of service after it has cleared the elevator that bypassed it, or has cleared any other elevator car in that bank for a distance, for example, of three floors, so that it will perform the most work possible without creating a confusion of cars at any level in the bank.

Every car has its exciting lamp E "on" and the apparatus at an equivalent distance of three floors ahead of the location of its respective car in the direction in which it is going. This distance depends on the traffic in the building or the particular bank in which the car is located and it may be adjusted for either greater

equivalent distances or less equivalent distances. The exciting lamp of any car can affect the photo tubes D and F of any of the cars which are traveling in the same direction, so long as said car is in service (not by-passed).

From the above, it will be evident that if the elevators are traveling in either direction at the proper space intervals, there is no interaction between the exciting lamps and the photo cells and the system operates normally. However, if one elevator, for example, is overtaking the one which precedes it, and the preceding one is destined to stop at a given floor, due to the pressing of the button in the hall by a prospective passenger, the selective bypass relay for the overtaking elevator is automatically thrown to the "off" position, with the result that the operator of that car does not get a signal to stop at that floor, nor does the indicating light for that shaft on the hall light up to confuse the prospective passenger, because the relay 178 also controls the supply of current to the hall lights. A pair of contacts 186 are mounted on arms which are connected to the positive side of the source 120 and to a conductor 187 which leads to the hall lights, and a conductor 188 is the return circuit for the hall lights and this is connected to the wire 121 which is in turn connected to the negative side of the source of current.

When the winding 179 of the relay 178 is energized in the manner described above that is to say, by the shifting of the relay 143 to the "off" position, or by actuating the operator's or the starter's switch 181 or 182, the arm 183 which is attracted by the core of the winding 179 is moved to the right, as seen in Figure 6, and as described above, but in addition to breaking the contacts 176 which interrupts the supply of current to the exciting lamps E₁ and E₂, the contacts 186 are also broken, thereby depriving the hall lights of current from source 120.

It is preferable that the potentiometers 137 and 168 be so set that in the event that both 45 windings of the bypass control relay 143 receive current, the "off" winding 182 shall receive more current than that received by the "on" winding 155, so that the "off" winding will actuate the bypass control relay whenever this occurs. It 50 is obvious that if desired, the "on" winding can be caused to receive more current than the "off" winding when the opposite effect is desired, by adjusting said potentiometers accordingly.

Although I have herein shown and described 55 by way of example, one embodiment of my new and improved elevator control system, it is obvious that many changes may be made in the arrangements herein shown and described and within the scope of the following claims.

60 What is claimed is:

1. In a control system for elevators, a movable support for and means to move the same in definite time relation with the movement of each elevator, the paths of travel of each of said supports being parallel to and coextensive with each other, photo-electric means and exciting lamp means carried on each support and arranged so that the exciting lamp means on any support may shine on the photo-electric means on any other of said supports which comes in its range, bypassing means on each elevator, and connections between the photo-electric means on each support and the bypassing means on its corresponding elevator for actuating said bypassing means.

2. In a control system for elevators, a movable support for and means to move the same in definite time relation with the movement of each elevator, the paths of travel of each of said supports being parallel to and coextensive with each other, photo-electric means and exciting lamp means carried on each support and effective when the elevator with which it corresponds is ascending, other photo-electric means and exciting lamp means carried on each support and effective when its corresponding elevator is descending, bypassing means on each elevator, and connections between the bypassing means of each elevator and both sets of photo-electric means on its corresponding support, so that the bypassing means on any elevator is actuated by the photo-electric means when the exciting lamp means of any other elevator moving in the same direction illuminates the same.

3. The method of controlling elevators by individual light and photo-electric means exercising control over the bypass means on each elevator car, which consists of moving said exciting lamp means and photo-electric means along coextensive paths in time with the movement of each elevator car, the step of amplifying currents generated in the photo-electric means of any car by virtue of light shining thereon from the light means of another car, and the final step of causing amplified current to actuate the bypassing means of one of the cars involved.

4. The method of controlling elevators by individual light means and photo-electric means exercising control over electro-magnetically actuated bypass means on each elevator car, which consists of moving said light means and photo-electric means along coextensive paths in time with the movement of each elevator car, amplifying currents generated in the photo-electric means of any car by light received from the light means of another car, and causing the amplified current to actuate the bypassing means of the car whose photo-electric means received said last light.

5. In a control system for elevators, a movable support for and means to move the same in time relation with the movement of each elevator car, the paths of travel of each of said supports being parallel to and coextensive with each other, other means to move said supports in a direction angular with respect to said first movement, one set of photo-electric means and exciting lamp means also carried on each support in spaced relation to said first set, whereby one of the sets on each arm moves in one zone and the other sets on each arm move in a second zone, the means in one of the sets being made effective when the direction switch of its elevator is thrown to the "descending" position and the other of said sets being made effective when the direction switch is thrown to the "ascending" position, amplifier means connected to the outputs of said photo-electric means, and electro-magnetic means on the bypass relay of each car adapted to be actuated by said magnetic means.

6. In a control system for elevators, individual light means and photo-electric means arranged in sets and moved in time with and in the directions corresponding to the movement of the elevator cars, electro-magnetically actuated bypassing means on each car, each of said sets being moved along coextensive paths in time with the movement of each elevator car with which it is associated, amplifying means connected to each

photo-electric means and interconnected with said bypassing means, whereby amplified currents generated in the photo-electric means of any car by light received from the light means of another car effects the actuation of the bypassing means of the car whose photo-electric means received said last light.

7. In a control system for elevators, a plurality of supports movable along paths which are parallel to and coextensive with each other, one of said supports being provided for each elevator car, individual electrical means connected to each of said supports for moving the same, means engaged by each car for controlling the electrical means of the support with which it is provided, exciting lamp means and photo-electric means carried on each support, electro-magnetically actuated bypassing means on each elevator car, amplifier means having its input connected to receive and amplify currents generated in the photo-electric means on one of said cars by light received from the exciting lamp of another of said cars, and connections between the output of said amplifier for delivering amplified currents to the bypassing means of the car whose photo-electric means received said last light.

8. In a control system for elevators, a plurality of supports movable along paths which are parallel to and coextensive to each other, one of said supports being provided for each elevator car, individual electrical means operatively connected to each of said supports, individual means for each car for controlling the electrical means of the support with which it is provided, said individual means being in turn controlled by the movement of the elevator car with which it is associated, exciting lamp means and photo-electric means carried on each support, electro-magnetically actuated bypassing means on each elevator car, amplifier means having its input connected to receive and amplify currents generated in the photo-electric means on one of said cars by light received from the exciting lamp means of another of said cars, and connections between the output of said amplifier for delivering amplified currents to the bypassing means of the car whose photo-electric means received said last light.

9. In a control system for elevators, a plurality of supports movable along paths which are parallel to and coextensive with each other, one of said supports being provided for each elevator car, individual means for each car for controlling the electrical means of the support with which it is provided, said individual means being in turn controlled by the movement of the elevator car with which it is associated, each of said supports carrying one set comprised of exciting lamp means and photo-electric means which is made effective when the elevator car with which it is associated is ascending, and a second like set spaced apart from said first set and made effective when said last mentioned car is descending, electro-magnetically actuated bypassing means on each elevator car, amplifier means having its input adapted to receive and amplify currents generated in the photo-electric means of one of said sets, corresponding to one of said cars, by light received from the exciting lamp means of a corresponding set on another of said supports controlled by another of said cars going in the same direction, and connections between the output of said amplifier and the bypassing

means of the car whose photo-electric means received said last mentioned light.

10. In a control system for elevators, a motor magnetic direction control for each elevator car, a plurality of supports movable along paths which are parallel to and coextensive with each other, one of said supports being provided for each elevator car, individual electrical means operatively connected to each of said supports for moving the same along one of said paths, individual means for each car and actuated thereby for controlling the electrical means of the support with which it is provided, each of said supports carrying one set comprised of exciting lamp means and photo-electric means, and a second like set spaced apart from the first set, said sets being interconnected with said motor magnetic direction control, said first set being made effective when the elevator car with which it is associated is ascending, and the second set being made effective when said last car is descending, electro-magnetically actuated bypassing means on each elevator car, amplifier means having connections to said motor magnetic direction control and adapted to receive and amplify currents generated in the photo-electric means of one of said sets corresponding to one of said cars by light received from the exciting lamp of a corresponding set on one of said supports controlled by another of said cars moving in the same direction, and connections between the output of the amplifier and the bypassing means of the car whose photo-electric means received said last mentioned light, said last connections also being controlled by said motor magnetic direction control.

11. In a control system for elevators, a motor magnetic direction control for each elevator car, a plurality of supports movable along paths which are parallel to and coextensive with each other, one of said supports being provided for each elevator car, individual electrical means operatively connected to each of said supports for moving the same along one of said paths, individual means for each car actuated thereby for controlling the electrical means of the support with which it is provided, each of said supports carrying one set comprised of exciting lamp means and photo-electric means, and a second like set spaced apart from the first set, said sets being interconnected with said motor magnetic direction control so that the first set is made effective when the elevator car with which it is associated is ascending and the second set is made effective when the last mentioned car is descending, means connected to each of said supports for moving it laterally in one direction when said first set is made effective and in the opposite direction when said second set is made effective, electro-magnetically actuated bypassing means on each elevator car, amplifier means having connections to said motor magnetic direction control and adapted to receive and amplify currents generated in the photo-electric means of one of said sets corresponding to one of said cars by light received from the exciting lamp means of a corresponding set on one of said supports controlled by another of said cars moving in the same direction, and connections between the output of the amplifier and the bypassing means of the car whose photo-electric means received said last mentioned light, said last connections also being controlled by said motor magnetic direction control.

12. In a control system for elevators, individual photo-electric means and exciting lamp means

remote from and moved in time with each elevator and arranged so that the exciting lamp means moving in time with any elevator may shine upon the photo-electric means moved in time with any other elevator as they move in line with each other, and circuits interconnected with said photo-electric means and the bypassing means on at least one of said elevators for bypassing one of the elevators involved.

13. In a control system for elevators, a plurality of movable supports remote from said elevators and adapted to move along definite predetermined paths which are parallel to and coextensive with each other, one support for each elevator of a bank, means between each elevator and its corresponding support for moving said support in timed relation to its elevator's movement, photo-electric means and exciting lamp means carried on each support and arranged so that the exciting lamp means on any of said supports may shine on the photo-electric means on any other of said supports which comes in its range, bypassing means on each elevator, and connections between the photo-electric means on each support and the bypassing means on its corresponding elevators for actuating said bypassing means.

14. In a control system for elevators, a plurality of movable supports remote from said elevators and adapted to move along definite predetermined paths which are parallel to and coextensive with each other, one support for each elevator of a bank, means between each elevator and its corresponding support for moving said support in timed relation to its elevator's movement, photo-electric means and exciting lamp means carried on each support and effective when the elevator with which it corresponds is ascending, other photo-electric means and exciting lamp means carried on each support and effective when its corresponding elevator is descending, bypassing means on each elevator, and connections between the bypassing means of each elevator and both sets of photo-electric means on its corresponding support, so that the bypassing means on any elevator is actuated by the photo-electric means corresponding thereto when the exciting lamp means of any other elevator moving in the same direction illuminates the same.

15. In a control system for elevators, a plurality of supports remote from the elevator cars and movable on a common axis, individual means each controlled by the movement of an associated elevator for moving a corresponding one of said supports on its axis, exciting lamp means and photo-electric means on each support, whereby the exciting lamp means on one support may shine on the photo-electric means on another support, and circuits between said last photo-electric means and instrumentalities for effecting controls remote from said supports.

16. In a control system for elevators, a plurality of supports remote from the elevator cars and movable on a common axis in two directions, individual means each controlled by the movement of an associated elevator car for rotating a corresponding one of said supports on said axis in one direction when the car is ascending and in the opposite direction when said car is descending, exciting lamp means and photo-electric means on each support, whereby the exciting lamp means on one support may shine on the photo-electric means on another support moving in the same direction, and circuits between said last photo-electric means and instrumentalities for effecting controls remote from said supports.

17. In a control system for elevators, a plurality of supports remote from the elevator cars and movable on a common axis in two directions, individual means each controlled by the movement of an associated elevator car for rotating a corresponding one of said supports on said axis in one direction when the car is ascending and in the opposite direction when said car is descending, exciting lamp means and photo-electric means on each support, each constituting a set, a second set of exciting lamp means and photo-electric means on each support in spaced-apart relation to the first set thereon, circuits between both sets on each support and the magnetic direction control of its corresponding elevator, electrically controlled means for and operatively connected to each support and electrically connected to the magnetic direction control of its associated elevator for decreasing the radius of each support when its elevator is moving in the opposite direction, whereby the exciting lamp means of one set on one support may shine on the photo-electric means for the corresponding set on another support moving in the same direction, and circuits between said last photo-electric means and instrumentalities remote from said supports.

18. In a control system for elevators, a movable support, the movement in a plane along a predetermined path of which is remotely controlled by an elevator, at least a second support moved along a plane coextensive with said first plane under control of a second elevator, photo-electric means carried on one of said supports, exciting lamp means on the other of said supports and facing in a direction to shine on said photo-electric means when it comes into registration therewith, and circuits between said photo-electric means and instrumentalities for effecting controls remote from said supports.

19. In a control system for elevators, a plurality of supports remote from the elevator cars and movable along coextensive planes, individual means each controlled by the movement of an associated elevator for moving a corresponding one of said supports on its path, photo-electric means and exciting lamp means carried on each support, whereby the exciting lamp means on one support may shine on the photo-electric means on any other of said supports which moves into the range thereof, and circuits between each of said photo-electric means and instrumentalities for effecting controls remote from said supports.

20. In a control system for elevators, a movable support, the plane along a predetermined path of which is remotely controlled by an elevator,

a second movable support moved along a plane coextensive with said first plane under control of a second elevator, photo-electric means and exciting lamp means positionably carried on each of said supports and each having two common positions thereon spaced apart from each other, magnetic means on each support for moving the photo-electric means and the exciting lamp means thereon into one or the other of said positions, a pair of circuits between each of said magnetic means and a source of current, one circuit of each pair being energized in time with the starting of its elevator car in one direction and the other being energized in time with the starting of its elevator in the opposite direction, and circuits between each of said photo-electric means and instrumentalities for effecting controls remote from said supports, whereby the exciting lamp means on one of said supports can only register with the photo-electric means on the other support and effect when both said elevator cars are moving in the same direction.

21. A system according to claim 20, in which the predetermined paths of said movable supports are circular and in which the photo-electric means and exciting means on each support are movable from one radius to a longer radius and vice versa.

22. In a control system for elevators, a plurality of supports remote from the elevator cars and movable in circular paths on a common axis, individual means each controlled by the movement of an associated elevator for moving a corresponding one of said supports along said path on one radius when the car is moving in one direction and along a different radius when the car is moving in the opposite direction, exciting means and photo-electric means on each support, whereby the exciting means on supports corresponding to elevators moving in one direction may only shine on the photo-electric means on other supports corresponding to other elevators moving in the same direction, and circuits between said last photo-electric means and instrumentalities for effecting controls remote from said supports.
